UNITED STATES PATENT OFFICE.

FRANK MOON, OF OAKLAND, CALIFORNIA, ASSIGNOR TO MOON TRACTOR CO., OF SAN FRANCISCO, CALIFORNIA, A CORPORATION OF CALIFORNIA.

TRACTOR-CARRIAGE.

1,374,384.

Specification of Letters Patent. Patented Apr. 12, 1921.

Application filed October 29, 1919. Serial No. 334,303.

To all whom it may concern:

Be it known that I, FRANK MOON, a citizen of the United States, residing at Oakland, in the county of Alameda and State 5 of California, have invented certain new and useful Improvements in Tractor-Carriages, of which the following is a specification.

My invention relates to a truck or carriage for tractors of the type using endless 10 articulated treads or track-chains.

The object of my invention is to provide a simple and strong carriage for supporting the major portion of the weight of the tractor by means of wheels or rollers operating 15 upon the lower run of the track chain, said carriage being flexibly connected with the tractor frame through weight-supporting springs, so that practically the entire weight of the tractor is spring supported, 20 thereby relieving its machinery from destructive jarring. Another object of my invention is to provide means associated with the carriage for supporting the upper run of the track-chain, so that the distance between 25 the upper and lower runs of the chain, and therefore, the tension on said chain, will be constant at all times irrespective of the movement of the tractor frame relatively to the carriage.

With this in view my invention will now be more fully described with reference to the accompanying sheets of drawings, wherein,

Figure 1 is a side elevation of my carriage, showing its relation to the tractor frame 35 and track-chain.

Fig. 2 is an end elevation of the same, taken on the line 2-2 of Fig. 1.

Fig. 3 is a sectional plan view taken on the line 3-3 of Fig. 1.

Fig. 4 is a central longitudinal section, enlarged, of one of the weight-supporting 40 rollers.

The reference numeral 1 designates a track-chain, shown only in Fig. 1. 2 designates the main longitudinal frame members 45 of the tractor, of which there are two for each track-chain, the spacing of said members being shown in Figs. 2 and 3. Inside of and parallel with the frame members 2 50 are guide members 3, secured to said frame members as by means of rivets 4 and spaced therefrom by spacer blocks 5, Fig. 3, leaving apertures 6, between guide members and said frame members.

55 The carriage proper comprises a pair of

spaced parallel longitudinal members 7, Figs. 1 and 2, to which are fixed upwardly extending vertical guides 8 and 9, the center pair of guides 8 being longer than end guides 9. Extending between the longitudinal members 7, preferably at the intersection therewith of the vertical members 8 and 9, are spindles 10, Fig. 1, upon which are journaled rollers 11, Figs. 1, 2, and 3, adapted to operate on the lower run of the track-chain 1. A similar roller 11', Fig. 1 journaled upon a spindle 10', is mounted between the upper ends of the center guide members 8 to support the upper run of said track-chain 1.

The rollers 11 and 11' are all similar in construction, as shown in Fig. 4, having bushings 12 surrounding and having bearing upon the spindles 10 and 10'. The rollers are hollow, as shown, forming reservoirs for lubricant, and are provided with filler plugs 13. The bushings 12 are perforated, as at 14, to permit access to the lubricant to the journal, and are provided at their ends with suitable packing 15, retained by rings 16, to prevent the lubricant from working out. Nuts 17 are provided for retaining the spindles 10 and 10' securely in their respective positions.

The vertical carriage members 8 and 9 pass freely through the guide apertures 6 of the frame structure, thereby retaining the carriage in position while allowing it to have some up and down movement relative to the frame. This up and down movement 85 is controlled and limited by springs interposed between the carriage and the frame, each of which I prefer to construct as a single semi-elliptical member 18, Figs. 1 and 2 whose ends rest upon the longitudinal carriage member 7 and whose arched center portion supports the tractor frame member 1 by bearing against the under side of the longitudinal guide member 3. There are, therefore, two of such springs for each carriage. The springs 18 are retained in position laterally by the vertical carriage members 8 and 9 upon one side, and by guide members 19 and 20, the former extending 90 downwardly from the end portions of the springs 18 and overlapping the sides of the longitudinal carriage members 7, and the latter fixed to the frame guide members 3 and bearing against the sides of the springs 17 in their central regions.

I claim:

1. In a tractor having an endless track-chain and a horizontal frame member provided with a vertically disposed guide-way; 5 a carriage comprising a horizontal member disposed beneath and spaced from said frame member, a vertical member secured to said horizontal member and passing freely through said guide-way, a weight-supporting roller carried by the lower portion of said vertical member and adapted to operate on the lower run of the track-chain to support the carriage, an idler roller carried by the upper portion of said vertical member and adapted to support the upper run of the track-chain, and a resilient connection between said carriage and said frame member for supporting the latter from the former.
- 10 2. In a tractor having an endless track-chain and a horizontal frame member provided with a vertically disposed guide-way; a carriage comprising a horizontal member positioned beneath and spaced from said frame member, a vertical member secured to said horizontal member and passing freely through said guide-way, a weight-supporting roller carried by the lower portion of said vertical member and adapted to operate on the lower run of the track-chain; an idler-roller carried by the upper
- 15 portion of said vertical member and adapted to support the upper run of the track-chain; and a semi-elliptic spring interposed between said horizontal carriage member 35 and said frame member for supporting the latter from the former.
- 20 3. In a tractor having spaced oppositely disposed horizontal frame members provided with vertically disposed guide-ways; 40 a carriage comprising oppositely disposed horizontal members positioned beneath said frame members, vertical members secured to said horizontal members and passing freely through said guide-ways, transverse 45 spindles extending between said horizontal carriage members, weight-supporting rollers journaled upon said spindles, a transverse spindle extending between the upper end portions of oppositely disposed vertical members, an idler roller journaled upon said upper spindle, and a pair of single-leaf springs, one positioned between each frame member and the corresponding horizontal carriage member.
- 25 55 In testimony whereof I have signed my name to this specification in the presence of two subscribing witnesses.

FRANK MOON.
